UNITED STATES PATENT OFFICE.

ANTON BECKER, OF COLUMBUS, OHIO, ASSIGNOR TO THE RALSTON STEEL CAR COMPANY, OF COLUMBUS, OHIO, A CORPORATION OF OHIO.

FLOOR-SUPPORT AND BOLSTER FOR HOPPER-CARS.

1,029,525.

Specification of Letters Patent.

Patented June 11, 1912.

Application filed January 30, 1909. Serial No. 475,257.

To all whom it may concern

Be it known that I, ANTON BECKER, a citizen of the United States, residing at Columbus, in the county of Franklin and 5 State of Ohio, have invented certain new and useful Improvements in Floor-Supports and Bolsters for Hopper-Cars, of which the following is a specification.

My invention relates to improvements in 10 car under-frames for hopper cars and especially includes means for supporting the slope or floor sheets of the hopper from the bolster.

The invention comprises primarily the 15 use of an angle or flanged member positioned upon and secured to the bolster diaphragms at its ends, and extending upwardly and engaging the bottom of the floor sheets, somewhat after the fashion of 20 an arch. This construction furnishes adequate support for the floor sheets, dispenses with the use of a multitude of rivets and requires much less material than is needed for the usual construction of supporting 25 means at the bolster for this purpose.

The invention further includes the use 30 of bracing and supporting means for the sides of the floor sheet preferably arranged vertically and associated with the bracing structure above described and with the bolster diaphragms.

The invention further comprises the use 35 of a transverse member having an inclined flange thereon to engage the floor sheets, to the vertical flange or portion of which the arch-like member and the vertical member above described are applied.

The invention comprises the features before mentioned and others, and their combinations 40 which will be hereinafter specifically set forth.

In the drawings which are hereto attached and hereby made a part of this specification, Figure 1 is a vertical transverse section 45 through a car provided with my improvements, the section being taken just at the rear of the bolster; Fig. 2 is a plan view of an end of the car showing the bolster construction to which my improvements 50 above mentioned are adapted to be applied; Fig. 3 is a sectional side view of an end of a car having my improvements applied thereto.

In the drawings, 1 indicates the center 55 sill formed in the construction here shown

of two parallel channels with their flanges 2 inwardly directed; the center brace 3 is positioned between the center sill channels, is appropriately flanged at 4 and is secured to the center sill by means of rivets 5; it is 60 provided with the opening 6 arranged for the insertion of the king pin.

On each side of the center sill and applied thereto by means of rivets passing through the center sill and through the center brace, 65 are bolster diaphragms 7 and 8; the bolster may be formed of a single diaphragm on one side of the center sill or a pair arranged on one side, both forms being well known, and either one being adapted for use with 70 my improvements. Underlying the center sill and the bolster diaphragms and extending from side to side of the car is a compression member 9 riveted at 10 to the lower flange of the bolster diaphragms. A tension member 11 overlies the center sill transversely and is secured by rivets 12 to the center sill and the upper flange of the bolster diaphragms. Sub side sills are shown 75 at 13 and 14, and side stakes 15 and 16 are 80 secured thereto by rivets as shown at 17 and 18.

An angle member 19 is provided with an inclined flange 20, and this flange is applied transversely from side to side of the 85 car to the floor sheets 21, and secured thereto preferably by riveting. A supporting member 22 is seated at its ends 23 and 24 upon the upper flanges 25 and 26 of the bolster diaphragms 7 and 8, and is riveted 90 thereto at 27 and 28 through its lateral flange 29; this supporting member is preferably bent upwardly from its seat on the bolster diaphragms to form the sloping or inclined portions 30 and 31, the upper portion 32 lying preferably in a horizontal plane and being secured through its vertical flange to the depending flange 33 on the transverse angle member 19. The supporting member 22 is thereby securely connected 100 with the transverse member secured to the floor sheets, and a supporting construction is thereby provided for the floor. The upper portion 32 of the supporting member 22 may be longer or shorter as desired, it being perceived that the general construction of this supporting member is that of an arch, with sufficient engagement with the flanged member depending from the floor sheets to form a substantial supporting con- 105 110

nection. The inclination of the portions 30 and 31 intermediate the bolster diaphragms and the floor sheets, produces a stronger construction than would be provided by any 5 other arrangement of these parts.

At each side of the car, vertical gusset angles 34 and 35 are provided, secured at their upper ends 36 to the depending flange 33 of the transverse member 19; the gusset 10 members are secured intermediate their ends at 39 to the bolster diaphragms, and at 40 to the vertical flange of the supporting member 22. Where two bolster diaphragms are used on each side of the center sill, I preferably employ two of the supporting members 15 22, and in that case fit the gusset angles 34 and 35 between the diaphragms and the supporting members, securing the same to both. Fig. 3 shows in vertical cross section a construction of bolster and supporting member 20 of this kind, the position of the gusset plate 35 being shown in Fig. 2.

The advantages of my improvement consist in dispensing with many rivets and 25 thereby much labor, a saving of material, providing a construction which supports somewhat on the arch principle, and securely tying together all of the members at the bolster and floor sheets and at the sides 30 of the car and at the lower sides of the bolster diaphragms in such manner that all the stresses incident to the use of the car are efficiently absorbed, and loosening and twisting of members is effectively obviated.

I do not desire to be confined to the specific constructions disclosed and described, 35 but wish to take advantage of any constructions which lie within the scope of the appended claims.

What I claim is:

1. In a hopper car, a bolster, a floor supporting member mounted thereon, a sub side sill, and a gusset member secured to said floor supporting member and bolster and sub side sill. 40

2. In a hopper car having a bolster and floor, a member secured transversely upon the under face of said floor, a supporting member having its ends applied to the upper face of said bolster on opposite sides 50 of the center sill, and having its middle portion bent upwardly into engagement with said transverse member, and a gusset member arranged vertically at the side of the car and secured in engagement with said 55 transverse member, supporting member, and bolster.

3. In a hopper car, a bolster, a floor supporting member mounted thereon, a sub side sill, and a gusset member secured to 60 said floor and floor supporting member and bolster and sub side sill.

In testimony whereof I affix my signature in the presence of two witnesses.

ANTON BECKER.
